UNITED STATES PATENT OFFICE.

JOHN A. GILLIES, OF AMSTERDAM, NEW YORK, ASSIGNOR TO McCLEARY, WALLIN & CROUSE, OF AMSTERDAM, NEW YORK, A CORPORATION OF NEW YORK.

DESIGN FOR A RUG.

SPECIFICATION forming part of Design No. 37,014, dated June 28, 1904.

Application filed June 3, 1904. Serial No. 211,024. Term of patent 3½ years.

To all whom it may concern:

Be it known that I, JOHN A. GILLIES, a citizen of the United States, residing at Amsterdam, county of Montgomery, State of New York, have invented a new, original, and ornamental Design for Rugs, of which the following is a specification, reference being had to the accompanying drawing, forming a part thereof.

10 The single figure of the drawing is a plan view of a rug embodying said design.

What I claim as new, and desire to secure by Letters Patent, is—

The ornamental design for a rug substantially as herein shown.

JOHN A. GILLIES.
